(57) **CLAIM**

I claim the ornamental design for roadside safety barriers, as shown and described.

DESCRIPTION

FIG. 1 is a front perspective view of a roadside safety barrier, showing my design;

FIG. 2 is a rear view thereof;

FIG. 3 is a front view thereof;

FIG. 4 is a side view thereof, the opposite side being a mirror image thereof;

FIG. 5 is a top view thereof; and,

FIG. 6 is a bottom view thereof.
